BUSHING FOR POLISHING WHEELS

James J. Manderscheid, Chicago, Ill.

Application July 24, 1944, Serial No. 546,425

6 Claims. (Cl. 51—168)

1

The present invention relates to polishing wheels and especially to a novel light weight bushing that may be readily inserted and permanently anchored in the opening in such polishing wheels.

Polishing wheels now on the market are each provided with a centrally disposed opening approximately $\frac{1}{8}$ inch less in diameter than the lathe spindle upon which it is to be mounted. The polishing wheel is then forced over the threads of the lathe spindle while the spindle is rotating. This procedure not only causes wear on the spindle but also endangers the operator as he must release the polishing wheel an instant before the wheel hugs the inside flange on the spindle or a dangerous hand burn results. Furthermore, this results in the opening being distorted out of round.

Among the objects of the present invention is to provide a novel construction of bushing for a polishing wheel that may be safely, readily and easily mounted in a polishing wheel whether old or new. It adds very little to the cost of the polishing wheel and when inserted, is automatically and rigidly connected thereto in operative relation. A polishing wheel equipped with the novel bushing is concentric throughout its entire circumference, is accurately balanced and thereby completely eliminates all chatter or uneven wearing surfaces. The work being polished with a wheel provided with the present bushing, will touch the face of the wheel along the entire circumference and thereby causing the emery or abrasive to wear uniformly and avoid all waste.

In the assembly of a polishing wheel equipped with the present novel bushing, it may be slipped over the polishing lathe spindle while the latter is stationary, so that neither the wheel nor the machine is turning when the former is placed on the spindle. Furthermore, the wheel is not forced over the threads either in putting it on or taking it off and thus no wear or damage on the spindle results.

The present invention contemplates making the bushings in certain standard spindle sizes such as 1, $1\frac{1}{4}$, $1\frac{1}{2}$, $1\frac{3}{4}$ and 2 inches in diameter, all with an inside tolerance of approximately plus .003. For example, a bushing that is to be fitted onto a spindle of $1\frac{1}{4}$ inch diameter, the inside dimension of the bushing is $1\frac{1}{4}$ plus .003 or 1.253 inches in diameter. The bushing although preferably made of suitable metal of relatively light weight having sufficient strength and rigidity to prevent distortion, may be constructed of any other material including plastic, rubber or

2

other composition suitable for the purpose and having the desired rigidity and inherent strength.

The present invention further comprehends a novel manner of anchoring the bushing onto the polishing wheel to thereby prevent it from coming out or turning in the wheel.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawing, and while there is shown therein a preferred embodiment, it is to be understood that the same is susceptible of modification and change, and comprehends other details, arrangements of parts, features and constructions without departing from the spirit of the invention.

In the drawing:

Figure 1 is a view in perspective of the novel bushing.

Figure 2 is an enlarged view in vertical cross section through the bushing.

Figure 3 is an enlarged view in side elevation of the polishing lathe spindle and showing the manner in which a pair of bushings may be mounted in a polishing wheel by using the polishing lathe spindle as a screw press.

Figure 4 is a fragmentary view similar to Figure 3 but showing the bushings assembled and forced into operative position in the polishing wheel.

Figure 5 is a view in side elevation showing a single bushing mounted in position and the polishing wheel so equipped assembled on the spindle.

Referring more particularly to the disclosure in the drawing, the novel embodiment selected to illustrate the invention comprises a bushing 1 having a cylindrical hub or collar 2 and a peripheral flange 3, the hub or collar being provided with a plurality of substantially triangular upstanding projections or notches 4 adapted to be embedded in the material of the polishing wheel 5 and thereby permanently and rigidly anchor the bushing in place. To facilitate insertion and to guide the hub or collar of the bushing into the opening in the polishing wheel, the edge of this hub or collar is tapered or feathered at 6.

In the assembly of the bushing 1 in the polishing wheel, it may be pressed into the opening 5 of either a new or old wheel by any suitable

means. One method that may be employed is to use the polishing lathe spindle 8 as a screw press. All that is required is to reverse the flanges 9 and 10 as shown in Figure 3 and by tightening the nut 11, the bushing or bushings are forced into the opening 7 and anchored therein by the projections, notches or tongues 4 as shown in Figure 4. Thereafter the nut 11 is backed off or unthreaded, and flange 10, polishing wheel and flange 9 removed in sequence. The flange 9 is then reversed and again applied to the spindle, after which the polishing wheel is slipped over the spindle, the flange 10 applied and the nut 11 drawn tight to lock the polishing wheel in operative position as shown in Figure 5, where a single bushing is employed. Generally but one bushing need be employed, but where the thickness of the wheel warrants, two may be applied.

These bushings are of light weight material such as approximately 16 gage drawn steel, although any other metal, or other substance including plastics, hard rubber or rubber-like compositions having sufficient inherent strength and rigidity to withstand the conditions of operation, may be used.

Whereas by the old method it was necessary to bore an opening approximately $\frac{1}{8}$ inch less in diameter than the diameter of the spindle on which the wheel was mounted, and to then spin the motor lathe spindle to mount the wheel, by the use of the present novel bushing, the wheels are bored to the size of the spindle and the wheel applied with the spindle stationary. For example, if a polishing wheel is to be mounted on a $1\frac{1}{4}$ inch spindle, the opening 7 is bored to that diameter and a $1\frac{1}{4}$ inch bushing is inserted. As this bushing has an internal diameter of approximately .003 inch larger than the diameter of the spindle, it is not forced over the spindle and there is no danger of damage thereto regardless of how often the wheel is assembled or replaced. Furthermore, as the wheel is applied to the spindle when stationary, there is no danger to the operator.

The hub or collar 2 is of such construction and length that the wheel is properly centered at all times and under all operating conditions. In the prior devices where the polishing wheel was provided with a smaller hole fitted or threaded over a larger spindle, considerable friction resulted which not only caused wear on the spindle but also distorted the hole or opening so that the wheel would be loose or hang on the spindle. The wheel being out of balance necessarily resulted in chatter.

The present novel bushing has universal application to any of the various types of polishing wheels now on the market regardless of the material of which the wheel is made, and is of such inexpensive construction that it adds but little to the cost of the wheel.

Having thus disclosed my invention, I claim:

1. A bushing adapted to be pressed into and automatically locked in a centrally disposed opening in a preformed polishing wheel, consisting of a member formed of relatively thin gauge metal

and provided with a peripheral flange and a hub portion, the latter adapted to be pressed into the opening and anchoring projections formed from the material of the hub and adapted to embed in the material of the wheel as the bushing is pressed into the opening.

2. A bushing adapted to be readily and easily inserted and anchored in the opening of a preformed and standard construction of polishing wheel, comprising a collar adapted to be pressed into the opening and of such length as to accurately mount the bushing in the opening and maintain the concentricity of the wheel, a flange formed at one end only of the collar and adapted to bear against a face of the wheel, and spaced projections on the circumference of the collar which become embedded in the material of the wheel when the collar is forced into the opening and thereby anchoring the bushing in the wheel.

3. A bushing adapted to be mounted in a centrally disposed opening in a new or old polishing wheel, consisting of a member formed of a light weight substantially rigid material providing a collar adapted to be forced into the opening, a flange at one end of the collar adapted to seat against a side of the wheel as the collar of the bushing is forced into the opening, and means on the collar for anchoring it into the material of the wheel surrounding the opening when the collar is forced into this opening.

4. In a standard construction of polishing wheel adapted to be mounted on a lathe spindle and provided with a centrally disposed opening, a bushing having a hub adapted to be received in the opening, spaced projections on the hub adapted to become embedded in the material of the wheel when the hub is pressed into the opening for anchoring the bushing therein, and a peripheral flange on one end only of the hub for locating the bushing in the wheel adapted to abut against a side of the wheel when the hub is pressed into the opening.

5. A bushing adapted to be readily mounted in either a new or old polishing wheel by the user, consisting of a collar adapted to be pressed into the opening and an integral flange at one end only of the collar and abutting against a side of the wheel when the collar is inserted to its proper depth, said collar being provided with a plurality of notches with integral projections so disposed as to anchor in the material of the wheel for securing together the wheel and bushing and preventing the bushing from turning in the wheel.

6. A bushing adapted to be readily assembled in an opening in a new or old polishing wheel, comprising a collar having an annular, peripheral flange at one end and its other end tapered to facilitate assembly and to guide the collar into the opening, projections formed from the material of the collar and projecting outwardly therefrom in such manner that as the collar is pressed into the opening, these projections interlock with the material of the wheel and prevent unintentional removal or turning of the bushing in the opening.

JAMES J. MANDERSCHEID.
